UNITED STATES PATENT OFFICE.

WILLIAM J. O'GORMAN, OF NEW YORK, N. Y.

SPARK-PLUG.

1,301,870.

Specification of Letters Patent. Patented Apr. 29, 1919.

Application filed April 29, 1918. Serial No. 231,331.

To all whom it may concern:

Be it known that I, WILLIAM J. O'GORMAN, a citizen of the United States, and a resident of New York, in the county of New York and State of New York, have invented certain new and useful Improvements in Spark-Plugs, of which the following is a specification.

My invention relates to spark plugs provided with one or more artificial gaps located in the head thereof and in the circuit of the ignition points of the plug such for instance as is described in my prior Patents No. 1,228,958, dated June 5th, 1917, and No. 1,268,049, dated May 28, 1918, the invention being more particularly an improvement on the spark plug described in the latter patent.

My invention consists among other things in providing a simple and compact plug having the above general characteristics and in dispensing with all but one terminal post or other projection on the head or block thereof, thereby simplifying the construction of the plug.

Other and further objects of the invention will appear from the subjoined description, the invention consisting in the novel parts and combinations of parts hereinafter more particularly described and then specified in the claims.

In the accompanying drawing:

Figure 1 is a vertical central section taken through my improved spark plug.

Fig. 2 is a side elevation of the same.

Fig. 3 is a front elevation of the porcelain or insulating core removed from the plug.

Fig. 4 is a horizontal cross-section taken on the line 4—4 of Fig. 1.

Referring more particularly to the several figures of the drawing:

1 indicates the insulating core of the plug provided with a slot 1' cut therein and carrying the lead wires or connections 2, 3 terminating in the spark points 4, 5 of the normal ignition gap. Said lead wires 2, 3 are held within the insulating core by suitable nuts engaging their upper ends and are provided with shoulders 4', 5' adjacent the spark points 4, 5 which are adapted to engage grooves in the insulating core to prevent turning of the lead wires within the core as illustrated. 6 indicates the metallic body or shell of the plug provided with the usual screw thread 7 for attachment of the plug to the engine.

8 indicates a clamping nut provided with upper and lower screw threaded sleeves 9 and 10 adapted to clamp and hold securely in position the metallic fastening plate 11 and the shell 6 respectively. Said metallic fastening plate 11 is provided, preferably adjacent the corners thereof, with holes 12 adapted to receive screws for attachment of the fastening plate to the rounded head or block 13 which is preferably constructed of fiber or hard rubber or other suitable insulating material.

The insulating head or block 13 is provided with chambers 13' extending transversely therethrough, within which the terminations or points 14 and 15 of the lead wires 2 and 3 respectively extend, the said points 14 and 15 constituting in conjunction with points 16 and 17, which also extend within the chambers 13', artificial spark gaps located in the circuit of the ignition gap. Point 16 is formed at the end of a return wire 18 which is entirely concealed and is embedded in the head or block 13 of the plug as illustrated. The opposite end 19 of the return wire 18 extends downwardly and slightly beyond the surface of head 13 and is adapted to enter a hole 20 in the metallic fastening plate 11. The point 17 forms the end of the main wire or terminal post 21 which is held to the head or block preferably at the extreme top portion thereof, as in the case of an ordinary spark plug, by a suitable nut and carries a binding screw for attachment of a leading in wire (not shown).

22 indicates a reserve or emergency spark point attached to the end of the metallic body or shell 6 of the plug and adapted to coöperate with the point 5 to form an ignition gap in the event of the failure of the main or principal ignition gap to function properly. 23 indicates suitable frames in which are mounted wire gauze members or members made of a translucent material and which are fastened to the head or block 13 and which close the chambers 13'. The wire gauze or translucent members prevent ignition of gas outside the plug but permit the points 14, 16 and 15, 17 to be seen to as certain if they are functioning properly.

In the usual operation of the plug the circuit is from the leading in wire through the main wire or terminal post 21, through the artificial gap at points 17, 15 by the lead

- wire 3, across the main ignition gap through points 5, 4, to the lead wire 2, across the artificial gap at points 14, 16, to the return wire 18 and to ground to wit: the metallic 5 fastening plate 11. In the event that the artificial gap 14, 16 does not function properly, the plug would still operate for the circuit in this case would be from the lead wire 3, across the gap 5, 22 and to the body 10 6. Obviously and as previously described in my prior patents, by means of the two artificial gaps in the circuit of the normal ignition gap the strength of the ignition spark is greatly increased.
- 15 The head or block 13 is formed of a solid piece, as illustrated, except that the chambers 13' and the holes for receiving the main wire 21, the return wire 18 and the ends of the lead wires 2 and 3, are provided or cut 20 therein, so that the central portion of the head itself with its downwardly extending projection 30, adapted to fit within the slot 1' of the insulating core 1, forms a barrier to prevent the passage of the spark across 25 from one artificial gap to the other directly and compels the passage of the current down to the ignition gap.

It will be obvious from the foregoing description that I have produced a simple and 30 compact form of spark plug provided with artificial gaps as previously described and having but one protruding terminal post or other projection on the head or block thereof, which could become damaged or out of 35 order and that the concealing of the return wire 18 in the manner described not only insures that wire from damage but makes for an attractive and graceful type of plug.

What I claim as my invention is:—

- 40 1. In a spark plug, the combination of an insulating core having conducting wires each terminating respectively at its upper end in points for an artificial spark gap, a main wire or terminal post protruding from 45 the spark plug and connecting with one of said artificial spark gaps and a concealed return wire connecting with the other of said spark gaps.

2. In a spark plug, the combination of an 50 insulating core, an insulating block to which said core is secured, conducting wires extending through said core and terminating at their upper ends in points for artificial spark gaps, the said block extending down-

wardly between the artificial gaps to form 55 an insulating barrier therebetween.

3. In a spark plug, the combination of an insulating core, an insulating block to which said core is secured, conducting wires extending through said core and terminating at 60 their upper ends in points for artificial spark gaps, a main wire or terminal post protruding from the insulating block and connecting with one of said spark gaps and a concealed return wire embedded in said 65 block and connecting with the other of said spark gaps.

4. In a spark plug, the combination of a metallic body, an insulating core fitting within said body, an insulating block, a 70 metallic fastening plate secured to said block, means for detachably joining together said metallic body and said fastening plate, conducting wires extending through said core and terminating in chambers in said 75 block to form two artificial spark gaps, a terminal post on said block connecting with one of said spark gaps and a return wire embedded in said block and connecting with the other of said spark gaps and engaging said 80 fastening plate.

5. In a spark plug, the combination of an insulating core provided with a slot cut in the upper portion thereof, an insulating block to which said core is secured, conducting wires extending through said core and terminating at their upper ends in points for artificial spark gaps and a downwardly extending projection on said block adapted 85 to fit within the slot in said insulating core 90 and to form an insulating barrier between the artificial spark gaps.

6. In a spark plug, the combination of an insulating core provided with grooves in the under side of the lower end thereof, conducting 95 wires extending longitudinally through said core and shoulders adjacent the lower ends of said conducting wires adapted to engage the grooves in said insulating core to prevent turning of the wires in said core. 100

Signed at New York, in the county of New York and State of New York, this 26th day of April A. D. 1918.

WILLIAM J. O'GORMAN.
